LIQUID FUEL BURNING APPARATUS

George F. Hodges and Fernando B. Cota,
San Ysidro, Calif.

Application June 19, 1933, Serial No. 676,554

1 Claim. (Cl. 158—81)

This invention relates to liquid fuel burning apparatus and has particular reference to one in which the burner is started by cold vaporization secured by a carbureting action in which air under pressure from the fuel tank impinges upon a nozzle supplied with liquid fuel from the tank, and in which a vapor generator is heated by the burner and receives the combustible mixture secured by cold vaporization only so long as it takes for the generator to become heated sufficiently for hot vaporization of liquid fuel, whereupon a thermostatic valve heated along with the generator is operated to shut off the delivery of air from the tank.

With these and other objects in view this invention consists in certain novel features of construction, combination and arrangement of parts to be hereinafter more fully described and claimed.

For a complete understanding of our invention, reference is to be had to the following description and accompanying drawing, in which:

Figure 1 is a vertical sectional view illustrating a liquid fuel burning apparatus constructed in accordance with our invention.

Figure 2 is a plan view illustrating the generator portion of the apparatus and the thermostatic means located adjacent thereto for controlling air under pressure to the apparatus.

Figure 3 is an end view illustrating the same. Figure 4 is a sectional view taken on the line 4—4 of Figure 1.

Referring in detail to the drawing, the numeral 1 indicates the main fitting or body of a liquid fuel burning apparatus having a mixing chamber 2 communicative with a generator tube 3 to which a suitable burner 4 is connected. A nozzle or jet 5 is located at one end of the chamber 2 and is communicative with a fuel passage 6 connected by a coupling 7 to a fuel supply pipe 8. The jet or nozzle at its discharge end is flared, as shown in Figure 4, and communicative with the chamber 2 laterally of the discharge or flared end of the jet or nozzle is an air passage 9 communicative with a chamber 10 formed in an enlargement 11 on the fitting 1 and which communicates with a bore 12 to receive a valve element 13 carried by an expandable and contractible stem 14. The bore 12 is connected through another coupling, like the coupling 7, to an air supply pipe 15 and when the valve 13 moves into the bore 12 the supply of air is gradually reduced and cut off to the chamber 10. The stem 14 is capable of sliding movement within the enlargement 11 and has

one end adjustably secured to a supporting frame 16 by nuts 17. The stem 14 is arranged to extend across the burner 4 with the generator tube 3 so as to be heated by the flame of the burner for expansion thereof. The stem 14 is thereby arranged to seat the valve 13 in the bore 12 to interrupt the flow of air. The valve 13 is provided with a groove 13' to prevent sudden cut off of the air pressure as the valve enters the bore.

A fuel reservoir 18 contains a liquid fuel under air pressure and has connected thereto a secondary fitting 19 provided with an air passage 20 and a fuel passage 21. The air passage 20 is connected to the pipe 15 and the fuel passage 21 is connected to the pipe 8 and also has connected thereto a pipe or tube 22 extending downwardly in the liquid fuel and terminating adjacent to the bottom of the reservoir.

The atomized fuel delivery from the main fitting 1 through the generator tube 3 to the burner 4 is controlled by a hand valve 23, which includes the usual needle point for fine adjustment of the orifice in the discharge end of the tube 3, the point being shown projecting from the discharge end of the tube in Figs. 1 and 2.

The drawing, for the purpose of convenience, has been made showing the various ports and passages larger than in the actual construction. Thus, for example, the opening in the fuel nozzle 5 is preferably, though not necessarily, .045" diameter; the air passage 9 is preferably, though not necessarily, .028" diameter, and the discharge opening of the valve 23 is preferably, though not necessarily, .025" diameter. The mixing chamber 2 which, it will be noted, is enlarged to accommodate the flared end of the fuel nozzle 5 is so proportioned with respect to the flared end as to leave, preferably, a very small clearance around it for air flow—an actual construction provided .0015" clearance. This slight clearance had the effect of restricting the air flow to the desired extent with relation to the fuel delivery, thus enabling dispensing with a separate air valve. However, the principal advantage of this lies in the fact that better vaporization results due to the thinness of the stream of air flowing past the periphery of the fuel nozzle. In fact, experiment proved that the smaller this clearance was made the better was the vaporization secured.

In operation, when the cold burner is to be started, the hand valve 23 is opened and combustible mixture produced by cold vaporization is discharged from the generator tube 3 to the

burner and ignited there, in any suitable manner. The air under pressure entering the chamber 2 impinges upon the fuel nozzle 5, annularly with respect to the flared end to produce a combustible mixture similarly as in a carburetor. This we term cold vaporization, because it is without the aid of heat, to distinguish it from the hot vaporization produced in the generator tube 3 when the same has been heated sufficiently by the burner 4. Cold vaporization continues until the burner 4 has heated the tube 3 to the fuel vaporizing point and has also heated the stem 14 sufficiently to close the valve 13 and shut off the flow of air from the tank 18, after which only liquid fuel is discharged from the tank into the mixing chamber 2 and flows from the chamber 2 in liquid form into the generator tube 3 for vaporization at that point, before delivery as a combustible vapor to the burner 4 in the usual way. There is a transition stage in which as the valve 13 gradually closes, less and less air is supplied to the mixing chamber, due to the action of the metering groove 13', so that the mixture produced in the chamber 2 gets richer and richer, until finally raw fuel is delivered to the generator 3 from the chamber 2. The generator 3, therefore, assumes its duty gradually as it heats up and at the proper temperature for the closing of the valve 13, the tube 3 is ready for the full duty of vaporizing raw fuel. When it is desired to

shut off the burner, it is only necessary to close the valve 23.

While we have shown and described the preferred embodiment of our invention, it will be understood that minor changes in construction, combination and arrangement of parts may be made without departing from the spirit and scope of our invention, as claimed.

Having described the invention, we claim:

In a liquid fuel burning device, a heating burner substantially horizontally disposed, a vapor generator therefor substantially horizontally disposed over said burner so as to be heated by the flame thereof, means for supplying liquid fuel under pressure to said generator, including a body having a mixing chamber therein, means for supplying air under pressure to said mixing chamber, a valve for controlling air flow into said chamber, a thermostatic element, one end of which is movable relative to said body, said element being substantially horizontally disposed over the burner so as to be heated by the flame thereof, said element being arranged to close said valve when heated to a predetermined temperature, and a supporting frame rigid with said body but extending beneath the burner so as to be out of the heat zone thereof, said frame having the other end of said element fixed thereto for support.
